CLAIM

The ornamental design for a belt decoration as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a belt decoration showing my new design;

FIG. 2 is a top view thereof;

FIG. 3 is a bottom view thereof;

FIG. 4 is a right view thereof; and,

FIG. 5 is a left view thereof.

The dashed lines and the masked portions surrounded by the dashed broken lines depict environment that forms no part of the claimed design.

1 Claim, 5 Drawing Sheets
